S. B. HESS.
ELECTRIC BURGLAR ALARM.
APPLICATION FILED MAY 27, 1907.

901,171.

Patented Oct. 13, 1908.

UNITED STATES PATENT OFFICE.

SIMON B. HESS, OF NEW YORK, N. Y.

ELECTRIC BURGLAR-ALARM.

No. 901,171.

Specification of Letters Patent.

Patented Oct. 13, 1908.

Application filed May 27, 1907. Serial No. 375,891.

To all whom it may concern:

Be it known that I, SIMON B. HESS, a citizen of the United States, and a resident of the city of New York, borough of Manhattan, in the county and State of New York, have invented a new and Improved Electric Burglar-Alarm, of which the following is a full, clear, and exact description.

This invention relates to an improved electric burglar alarm, and consists of means for starting an alarm bell if a person attempts to enter, break or cut through any of the windows, doors or transoms of the room or building, or if he attempts to interfere in any way with the bell or its protecting casing, and means whereby the bell will continue ringing until a person knowing the particular combination and possessing the proper switch-key, arrives to stop it.

More in detail, my invention comprises a main or protecting circuit having a battery and electro magnet and having portions of the circuit adjacent to all the windows, doors or other possible entrance openings which it is desired to protect. Interference with any of these will either break the circuit or short-circuit the electro magnet, and in doing so de-energizes the same and permits the armature to drop. The dropping of this armature closes a second or alarm circuit having its battery and electro magnet, and upon the energizing of the latter the bell circuit is closed and the clock-work started in operation. This clock-work is designed to cause the bells to ring intermittently and may be employed, if desired, to stop the operation of one or more of the bells after it has rung for a predetermined length of time. In order to stop the bells from ringing I provide an automatic self-restoring drop in which no permanent magnets are used, and which is controlled by a plurality of switches, one or more of which may be held in place by locks, whereby a person cannot stop the bell or bells unless he knows the particular combination of switches to turn and possesses the proper key or keys by which said switches may be unlocked and operated.

In the drawing I have illustrated diagrammatically a system of wiring and the combination of parts by which the result above described may be obtained.

The main or protecting circuit comprises a battery 1, the coils of an electro magnet 2, the protecting casings 3 and 4 of the alarm bells and all of the windows and doors of the

room. The casings for the bells are preferably formed of two concentric, metal boxes 5 and 6 having a layer of insulating material 7 therebetween, and the outer casing constitutes a part of the main circuit. The current normally flows from the battery 1 through a wire 8 to the outer box of the casing 4, through said casing and a wire 9 to the outer box of the casing 3. From here the current passes through a wire 10 to a strip of tin-foil 11 or other suitable conducting means surrounding each of the windows and the transom, and from the last of these to a contact 12 located on a door 13. This door 13 carries a removable screen having a wire 14 extending back and forth across the same and terminating at a contact 15. A wire 16 extends from the contact 15 on the door to a switch 17, from which the current flows through a wire 18, coils of the electro-magnet 2 and a wire 19 back to the battery 1. The return wire 19 is connected to the inner box of the casing 3 by means of a tap wire 20 passing freely through an opening in the outer box, whereby the electro magnet may be short-circuited if the two boxes are brought in contact or if any conductor, as, for instance, a screw-driver or other tool, is brought in contact with the two boxes simultaneously. In this case the current would flow through the wire 8, casing 4, wire 9, outer box 5 to the inner box 6 and return to the battery through wires 20 and 19.

Connected with the main circuit at a point 21 is a tap wire 22, having a branch 23 thereof extending to the inner box of the casing 4 and a second branch 24 extending to a contact located on the lower casing directly above the door and adapted to contact upon the opening of the door with a terminal 25 connected to the wire 16 and carried by the door. These tap wires form a shunt around the electro-magnet to short circuit the same if the door be opened or if a current is permitted to flow in any manner from the inner to the outer box of the casing 4. If this main circuit is broken at any point throughout its length, or if the battery or the coils of the electro magnet are short-circuited in any possible manner, the core of said electro magnet is de-energized and an armature 26 allowed to drop onto a platinum point located directly beneath the same. This closes the second circuit and permits the passage of a current from a battery 27 through a wire 28, armature 26, switch 29, wire 30, the

coils of an electro magnet 31, a wire 32, contact members 33 and 34 of a switch and wire 35, back to the battery 27.

A current flowing through the second circuit energizes the electro magnet 31 and draws down its armature 36, one end of which slides past a catch 37 adapted to hold the armature in contact with the electro magnet, while the other end is provided with 10 a hook normally contacting and holding in position the fan-wheel 38 of the clock-work, and also adapted to slide on a contact 39 and close the bell circuit.

The clock-work above referred to comprises a spiral spring 40 which, in uncoiling, starts in motion a train of gears comprising a wheel 41, a pinion 42, wheel 43, pinion 44, wheel 45, pinion 46, wheel 47 and pinion 48 carrying the fan-wheel 38. The wheel 43 20 carries a plurality of pins 49 which, upon the rotation of the wheel, come successively in contact with a spring terminal 50, while the wheel 45 carries a much larger number of pins contacting successively with a spring 25 terminal 51. All of these wheels and pinions are mounted on a metal plate 52 but are not insulated therefrom, whereby the plate and gears may constitute a portion of the bell circuit. The wheel 41 carries an arm 53, having 30 the outer end thereof insulated from the remainder and adapted to contact and move two switches 54 and 55 mounted on a smaller plate insulated from the main plate 52.

As the bell circuit is closed by the energizing 35 of the electro magnet 31 and the contact of the armature 36 and terminal 39, the current flows from the battery 27 through the wires 56 and 57 to the switch 54, whereby the single stroke bell is rung, and then flows 40 through the wire 58 to the terminal 51 and through the gears and plate 52 to the wire 59, armature 36, contact 39, wire 60, fingers 61 and 34 of the switch and back to the battery through the wire 35. In this manner 45 the single stroke bell is rung each time the spring terminal 51 comes in contact with a pin on the wheel 45. Meanwhile a branch circuit is formed from the wire 56 through the wire 62, the vibrating bell in the casing 4 50 and wire 63 to the switch 55, from which it flows through a short connection 64 to the plate 52 and there joins the current from the single stroke bell and returns to the battery 55 as above described.

If it is desired to shut off the single stroke bell or to ring the vibrating bell only intermittently, I provide the switches 54 and 55 with short pins extending into the path of the arm 53. As this arm swings around it 60 moves the switch 54, thus stopping the single stroke bell, and a short time later moves the switch 55. After the switch 55 is thrown, the current can flow from the vibrating bell back to the battery only by passing through 65 the wires 63 and 65 to the spring terminal 50,

which contacts with the pins 49 of the wheel 43 as the latter rotates. These pins 49 are preferably few in number and located a considerable distance apart, whereby the vibrating bell is rung intermittently as each of the 70 pins 49 reaches the terminal 50 and permits the passage of a current from said terminal to the plate 52 and wire 59.

As any suitable chain of gearing may be employed as well as a spring of any desired 75 length, it is evident that when the protecting circuit flowing from the battery 1 is broken or short-circuited in any manner, the two or more alarm bells will ring either continuously or intermittently for a great length of time, 80 determined only by the life of the batteries and the tension of the spring 40. Even although the protecting circuit is broken or short-circuited for only a fraction of a second, this short interval of time is amply sufficient 85 for the armature 26 to drop, and the arm 36 to become locked in position by the catch 37 to close the alarm circuit.

The ringing of the bells may be stopped at any desired time by the manipulation of certain switches located in any convenient place, but I preferably provide such a number of switches, certain of which are essential and certain of which are non-essential, that it is practically impossible for a person to stop the 90 ringing of the bells unless he is informed as to the particular combination of switches which it is necessary to operate in order to accomplish the desired result. As shown, these switches are four in number, two of which, 17 95 and 29, are normally closed while the other two, 66 and 67, are normally open, and any one or more of these switches may be held in their normal position by locks or other key or combination controlled mechanism. When the 100 person in possession of the proper keys and knowledge of the proper switches to manipulate, arrives, the switches 17 and 29 are opened and the switches 66 and 67 are unlocked 105 and closed. The current from the battery 27 110 may then flow through the wire 28, switches 66 and 67, wire 68, coils of the electro magnet 69 and back to the battery by a wire 70, whereby the core of the electro magnet 69 is energized and the catch 37 on the armature 115 is drawn away from the end of the armature 36. This allows the spring to pull down the end of the armature 36 and break the bell circuit at 39 and interfere with the fan-wheel 38 to stop the clock-work. As soon as the protecting circuit is again intact the switches are 120 thrown back into their normal position, as indicated on the drawing, and the system is thus automatically restored to its operative condition.

All the parts of the system, and particularly the clock-work and electro magnets, are concealed within the walls or beneath the floor of the room, and the only parts exposed are the bell casings and the switch-board. 130

The switch-board may, if desired, consist of a large number of push buttons so connected that to stop the ringing of the bells it is necessary to push certain of them simultaneously and avoid pushing certain others, whereby only a person knowing the proper buttons to be pushed can stop the ringing of the bells. The bells and bell casings may be located at any point desired, and the wires leading to the bells preferably enter the casing from the side which is secured to the support, whereby the bell wires are thoroughly concealed. If a person attempts to disconnect the bell to prevent its ringing and giving an alarm, it is practically impossible for him to do so without either breaking the wires connected to the outer box of the casing, which would set off the alarm, or bringing some tool or implement in contact with both the boxes at the same time, which would short-circuit the electro-magnet 2 and also set off the alarm. The bell casings are preferably provided with a large number of small openings so that the sound of the bell may be distinctly heard; but the insertion of any tool through said openings to injure or mutilate the bell would almost unavoidably produce a short-circuit and sound a warning.

In case the person knowing the combination by which the bells may be stopped is absent for a considerable length of time after the bells have once been started, it will be noted that as the spring 40 of the clock-work becomes unwound it will contact with a short lever 71 located adjacent thereto and thus disconnect the switch from the fingers 33, 34 and 61, which will stop the bells, but only after they have rung for several hours or even days, depending upon the length and tension of the spring 40.

In my improved electric burglar alarm as above described, it is impossible for any person to break or open any window, break or open the doors or remove the screen therefrom, or to mutilate or interfere with any of the bells without sounding an alarm; and this alarm cannot be stopped except by a person familiar with the proper method of doing so, while the alarm may be stopped and the entire system restored to its former condition in a few seconds by the proper manipulation of the switches.

Various changes may be made in the wiring, arrangement of the switches and construction of the clock-work and automatic restoring mechanism without departing from the spirit of my invention, as such changes will be obvious to one skilled in the art.

Having thus described my invention I claim as new and desire to secure by Letters Patent:

1. In an alarm system, a closed protecting circuit including a protecting casing for an alarm signal and an electro-magnet outside of said casing, an open shunt around said

electro-magnet including a second casing inclosing said alarm signal but spaced from the first-mentioned casing, and an alarm circuit controlled by said magnet and including the alarm signal within said casings and a source of electrical energy outside of said casings. 70

2. In an alarm system, an alarm signal, two concentric protecting casings inclosing solely said signal and spaced apart, a closed protecting circuit including an electro-magnet outside of said casings, said circuit being connected to said casings at opposite sides of the magnet, respectively, and an alarm circuit controlled by said magnet, including a suitable source of electrical energy outside of the casings, said signal within the casings and conductors extending through both casings but insulated therefrom. 75

3. In combination, an alarm circuit, including an alarm signal and a switch, and a mechanical motor including means for repeatedly making and breaking said circuit independently of the switch to operate the signal intermittently, and means independent of said last-mentioned means for throwing said switch after said alarm has been operated intermittently for a predetermined length of time. 80

4. In an alarm system, a protecting circuit, an alarm circuit controlled thereby including an alarm signal, a motor operating to limit the time of operation of the signal, means for releasing said motor upon the instantaneous breaking of the protecting circuit, and means including an electro-magnet 100 for stopping said motor at will. 95

5. In an alarm system, a protecting circuit, an alarm circuit including an alarm signal, a motor, means controlled by the protecting circuit for closing said alarm circuit and releasing said motor, means operated by the motor for repeatedly interrupting the alarm signal, means for holding said alarm circuit closed, and an electro-magnet 105 for releasing said holding means. 110

6. In an alarm system, a protecting circuit, an alarm circuit, a mechanical motor, means controlled by the protecting circuit for closing the alarm circuit and releasing said motor, retaining means adapted to engage with said last-mentioned means, an electromagnet for releasing said retaining means, and a manually-controlled switch for throwing said electromagnet into circuit. 115

7. In an alarm system, a protecting circuit, an alarm circuit controlled thereby including a battery, a signal, means for preventing the stopping of the signal upon the restoring of the protecting circuit, means for automatically stopping the signal after a predetermined length of time, and means including a plurality of circuit closers, by the simultaneous opening of some and the closing of others of which the signal may be stopped at will. 120

130

8. In an alarm system, a protecting circuit, an alarm circuit controlled thereby including a battery, a signal, means for preventing the stopping of the signal upon the restoring of the protecting circuit, means for automatically stopping the signal after a predetermined length of time, means including a plurality of circuit closers, by the simultaneous opening of some and the closing of others of which the signal may be stopped at will, and means for opening all circuits from said battery automatically after the alarm has been automatically stopped after a predetermined length of time.
- 15 9. In an alarm system, a protecting circuit, an alarm circuit including an alarm signal and an electro-magnet, a circuit closer operated by said electro-magnet, a catch engaging therewith for holding said circuit closed independently of the passage of a current through said magnet, a second magnet for releasing said catch, and a plurality of manually-controlled switches for stopping said alarm, one of said switches serving to break the circuit through the first-mentioned electro-magnet and another switch serving to close a circuit through the second magnet.
- 20 10. In combination a mechanical motor, an electromagnet, an armature therefor acting as a switch to close a circuit and also serving to control said motor, a second armature having a catch adapted to engage with the first-mentioned armature and retain it in one of its two positions, a second magnet for said second armature, serving to release the first-mentioned armature and permit the

opening of the switch, and manually-controlled means for closing the circuit to energize said last-mentioned magnet.

11. In combination, a protecting circuit including an alarm signal, a motor for controlling the time of operation of said signal, an electro-magnet, the armature of which serves as releasing means for said motor and also as a circuit closer for the alarm signal, and a second electro-magnet having the armature thereof adapted to engage with the first-mentioned armature and permit the continued operation of the motor and the holding of the circuit closed after the de-energizing of the first-mentioned magnet.

12. In an alarm system, a closed protecting circuit, including an electromagnet and wiring carried by a closure and so disposed that the breaking of the closure breaks the circuit, an open shunt around said magnet and including terminals adjacent said closure and adapted to be brought into contact upon the opening of the closure, and one of said terminals being connected to the wiring on said closure, whereby said opening of the closure will short-circuit the magnet, and an alarm adapted to be operated upon the de-energizing of said magnet.

In testimony whereof I have signed my name to this specification in the presence of two subscribing witnesses.
